[57] CLAIM

The ornamental design for a shut-off valve, as shown
and described.

DESCRIPTION

FIG. 1 is a left front perspective view of a shut-off valve
showing my new design, a right front perspective view
being a mirror image;

FIG. 2 is a left side elevational view, the right side being
a mirror image;

FIG. 3 is a front elevational view;

FIG. 4 is a rear elevational view; and,

FIG. 5 is a top plan view thereof.

FIG. 1

FIG. 2

FIG. 3

FIG. 4

FIG. 5
